CONTROL MEANS FOR SUBMARINE
INTERCEPTORS

William O. Harrison, Jr., Winchester, Ind.

Application June 1, 1949, Serial No. 96,565

2 Claims. (Cl. 114—16)

1

My present invention relates to the general class of submarine vessels of the torpedo discharging type, and more specifically to improvements in control means for submarine interceptors designed and constructed for carriage on and launching or lowering from a surface carrier, and when submerged especially adapted for intercepting and destroying enemy submarines as well as surface craft. The submarine interceptor, or torpedo boat carrying a two-man crew, is equipped with a cellular, streamlined hull which reduces drag to a minimum, and electrical propulsion mechanism to insure high speed, together with manually controlled systems of hydroplanes that facilitate submerging and ascending operations, together with steering mechanism for attaining maximum maneuverability of the craft, on the surface, as well as when submerged.

The improvements consist in novel features of construction and combinations and arrangements of parts as will hereinafter be described and more particularly pointed out in the appended claims.

In the accompanying drawings I have illustrated a complete example of a physical embodiment of my invention in which the parts are combined and arranged in accord with one mode I have devised for the practical application of the principles of my invention. It will however be understood that changes and alterations are contemplated and may be made in these exemplifying drawings and mechanical structures, within the scope of my claims, without departing from the principles of the invention.

Figure 1 is a vertical longitudinal sectional view of an interceptor or torpedo discharging vessel in which my invention is embodied; and Figure 2 is a horizontal longitudinal sectional view at line 2—2 of Fig 1.

Figure 3 is an enlarged vertical sectional view through the nose of observation compartment of the vessel.

Figure 4 is a transverse vertical sectional view at line 4—4 of Fig. 1.

Figure 5 is a transverse sectional view at line 5—5 of Fig. 1; and Figure 6 is a similar view at line 6—6 of Figure 1.

Figure 7 is a perspective view, with parts broken away, showing the manually controlled forward and rearward hydroplanes and the operating mechanism therefor; and

Figure 8 is a perspective view of the pedal operated steering mechanism.

In the preferred form of the invention shown 55

2

in the drawings an all-welded structure of magnesium, steel, or other suitable material includes a cellular streamlined hull capable of withstanding great hydraulic pressure, and made up of 5 an interior hull 1 and an exterior hull 2 spaced by welded bulkheads 3, which form separate water-tight cells. The interior of the vessel is longitudinally divided by two transversely arranged bulkheads 4 and 5 that provide a forward operators compartment, a main apartment amidship, and a rear engine compartment, the communicating openings between the compartments being provided with watertight doors or hatches 6.

15 The forward operators compartment terminates in a front bulkhead 7 having a circular opening that is surrounded by a welded sealing ring 8, and an observation compartment is provided in front of the operator's compartment that 20 is closed by a hemispherical nose 9, preferably of hardened plastic and transparent material, and fastened by screws as 10, or in other suitable manner to the bulkhead. The rear portion of the observation compartment is completed by a 25 double wall housing 11, in the shape of a truncated cone that terminates in an open frame 12, and a hermetically sealed plastic window 13.

For access to the observation compartment from the operators compartment, an emergency 30 hatch 14 is hinged at 15 and adapted to be closed by mechanism including a hydraulic motor 16 and its actuating rod 17, to prevent flooding of the operators compartment in the event the nose is broken or otherwise damaged.

35 By means of an electric search light 18 mounted back of the transparent nose, a wide area in front of the vessel is illuminated to afford an unobstructed vision of a target, for directing salvaging operations, and other under-water 40 operations such as discerning objects on the bottom of shallow waters. The symmetrical shape of the nose of the observation compartment conforms to the streamline contour of the cellular hull, to equalize distribution of hydraulic 45 pressure at great depths, and to eliminate drag that would otherwise impede the speed of the submarine.

A seat 19 is provided for the operator in his compartment, and he may readily make observations through the window 13 and the transparent nose, and an instrument panel 20 is mounted in the operators compartment for ready access of the occupant of the seat.

A floor or deck 21 is provided for the operators compartment, and the floor is equipped with op-

positively sliding and laterally arranged sectional doors 22, that may be opened outwardly to gain access to torpedoes T or other ammunition, stored in the chamber beneath the floor, for discharge through a torpedo tube 23 which opens through the bow portion of the vessel.

Other accessories, as a periscope 24, a snorkel tube 25, and the necessary main hatch 26 through the upper deck portion of the hull, are provided, together with radio equipment 27, and multiple oxygen tanks 28 for emergency use, are provided within ready access of the crew.

In the large amidship compartment a catwalk 29 is provided for convenience of the crew, and below the catwalk are stored the ballast tanks 30; and multiple electrical batteries 31 are spaced at opposite sides of the compartment to aid in stabilizing the vessel. The usual multiple compressed air tanks 32 are supported by clips on the opposite side walls of the hull for use in blowing the ballast tanks 30, and the trim tanks 33 that are located within both the operator's compartment and the aft compartment of the vessel.

The propulsion mechanism which is located in the rearmost or aft compartment includes an electric motor 34 having its shaft 35 connected with transmission gearing in the gear housing 36; and duplicate counter rotating propellers 37 and 38 are utilized for driving the vessel.

For steering and maneuvering the boat on a vertical axis, a rudder 39, which is pedal controlled from the seat in the operator's compartment, longitudinally extending steering gear is employed and actuated by the right and left or port and starboard pedals 40, 41, respectively. The gear includes sprocket and chain drives 42 and 43 that operate through a tubular drive shaft 44 to partially rotate a torque shaft or crank shaft 45, preferably of tubular formation and journaled in suitable bearings having fixed supports. This crank shaft or rock shaft 45 is connected by a rock arm 46 and a reciprocable rod 47 to a complementary rocker arm 48 on a rock shaft or torque tube 49 journaled in suitable bearings, and by means of a depending rocker arm 50 on shaft 49 and a connecting link 51 that is pivotally connected to an arm or horn 52 of the rudder 39, the rudder may be turned on its vertical axis or pin 53.

For controlling movement of the boat about its longitudinal axis, a manually operated pair of laterally arranged and outwardly projecting forward hydroplanes with balancing surfaces are mounted and disposed directly above the center of gravity of the boat to perform the functions of combination wings and ailerons for use in banking the progress of the boat under water, and for maneuvering in a short radius. The ballast tanks are used to change or determine the center of gravity. By filling or emptying the ballast tanks the center of gravity is raised or lowered. Thus when submerged the center of gravity will be higher than when the boat is on the surface. The forward hydroplanes are used therefore to permit movement about the longitudinal axis of the boat in the same manner as the ailerons of an airplane.

For this purpose a pair of outboard hydroplanes 54 and 55 are each equipped with an inwardly extending transversely arranged axle, as 56, each of which is partially rotated or rocked by a suitable gearing mounted in a gear box 57 mounted on top of a supporting bracket 58 that is fixed on a suitable support.

The gearing of the axle 56 of the right hand or port hydroplane 54 is directly activated by means of a sprocket and endless chain drive 59 through a longitudinally extending rock shaft 60; and the gearing for the axle of the left hand or starboard hydroplane 55 is directly activated by a complementary sprocket and endless chain drive 61 mounted on a bracket 58, and a longitudinally extending rock shaft 62 journaled in 10 suitable bearings.

The longitudinally extending rock shafts 60 and 62 enter into and are supported by bearings within a gear housing 63 located in the operator's compartment and under a portion of the observation compartment, and a control wheel 64, manipulated by the occupant of the seat 19 is mounted on a longitudinally extending and centrally located control shaft 65 that is journaled to turn on its axis. Power and motion are simultaneously transmitted from shaft 65 to the two parallel shafts 60, 62, through a sprocket and endless chain drive 66 to a double sprocket wheel 67 on a shaft 68, and an endless chain 69 drives sprockets 70 and 71 on the respective shafts 60 and 62.

Maneuvering of the boat about its lateral or transverse horizontal axis is also attained by a pair of outboard rear hydroplanes 72 and 73, under control of the wheel 64 in the hands of the operator, and for this purpose a coaxial and tubular control shaft 74 is slidably mounted on the shaft 65 and connected to the wheel and adapted to be reciprocated by a push and pull movement of the wheel. The coaxial shaft is equipped with a rigidly mounted block or lug 75 that is fastened to a link of an angularly disposed endless chain and sprocket drive 76 which bends over guide sprockets 77 and transmits power and rotary motion to a rock shaft or torque shaft 78 that extends transversely of the ship and is journaled in bearings of the housing 63. Upon shaft 78 are mounted two spaced rocker arms 79 and 80, to which the port rod 81 and the starboard rod 82 are respectively pivoted, and the rear ends of these rods are pivotally connected to rock arms 83 and 84 respectively which are mounted on a transverse shaft 85.

The two hydroplanes 72 and 73 are united by a transversely extending torque shaft 86 that is mounted for axial adjustment in suitable bearings, and each hydroplane is equipped with an arm 87 that is linked by rods 88 and 89 to the rock arms 83 and 84 of the shaft 85.

One important feature of the boat embodying the invention is that the design almost approaches a perfect streamline body which reduces drag to a minimum. The shape of the body permits very high speed to be obtained and the boat is highly maneuverable due to its type of control.

Once the boat has attained suspension by means of its ballast tanks it is trimmed up by the trim tanks and the controls can then be used to descend or ascend whichever is desired.

Another advantage of this particular boat is that the props are reversible so that you can attain backward motion or the props can be used as a braking action for slowing the forward speed of the boat. The function and operation of the controls are as follows: The movable controls surfaces are all of the balance type. Controls are used exactly in the same manner as are airplane controls. The forward hydroplanes being used for a combination wing and aileron movement about the longitudinal axis is controlled therefore by the forward hydroplanes in the same

manner as the airplane is controlled by the ailerons. The forward hydroplanes are placed in line with the center of gravity just as the wings of an airplane are located on the approximate line to the center of gravity. The forward hydroplanes can therefore be used so that the boat can be banked under water and maneuvered in a short radius which could not be obtained without the use of the hydroplanes. The rear hydroplanes are used as elevators for movement about the lateral axis. Movement about the vertical axis is obtained by the rudder. The proper bank of the boat is established by coordinating the hydroplanes and rudder.

The use of a transparent plastic nose aids in the operator's visibility and thereby reduces the distance to an object which he wishes to observe. It also affords other unobstructed vision forward over a wide area. With the plastic nose the boat can be used in shallow water to observe objects on the bottom. In the event that the nose is damaged an emergency hatch can be closed hydraulically to prevent the operator's compartment from being flooded. The symmetrical shape of the nose permits an equal distribution of pressure so that the nose is capable of withstanding the enormous pressure involved at great depths.

Having thus fully described my invention what I claim as new and desire to secure by Letters Patent is:

1. In a balancing system for a submarine boat the combination comprising a forward pair of oppositely disposed horizontally projecting hydro-planes, an axle connected to the inner end of each hydro-plane and extending inwardly of each hydro-plane in the same plane, a gear box connected to the inner end of each axle, a rock

shaft extending forwardly of each gear box in a horizontal plane with the axis of each rock shaft extending at right angles to the axis of said axles, chain drive connections between each forwardly extending rock shaft and the gear box, a shaft extending intermediately of said rock shafts parallel thereto, a chain drive connection between said last shaft and said rock shafts, and a control mechanism connected to said last shaft for controlling the operation of said hydro-planes.

2. A balancing system as in claim 1 wherein an aft pair of oppositely disposed horizontally projecting hydro-planes is provided and a separate controlling mechanism is provided for said aft pair of oppositely disposed horizontally projecting hydro-planes and means is provided for operatively connecting the control mechanism of the forward hydro-planes to the control mechanism of the aft hydro-planes.
